CLAIM

The ornamental design for a pushbutton actuator for an electrical switch, as shown and described.

DESCRIPTION

FIG. 1 is a perspective view of a pushbutton actuator for an electrical switch, showing my new design;
FIG. 2 is a front elevational view of FIG. 1;
FIG. 3 is a side elevational view of FIG. 2;
FIG. 4 is a top plan view of FIG. 1; and,
FIG. 5 is a bottom plan view of FIG. 1.

The side opposite to FIG. 2 is identical to FIG. 2 and the side opposite from FIG. 3 is identical to FIG. 3.

FIG. 1

FIG. 2

FIG. 3

FIG. 4

FIG. 5
